CLAIM

The ornamental design for a ponytail hairnet, as shown and described.

DESCRIPTION

FIG. 1 is a front view of a ponytail hairnet showing my new design in a worn configuration;

FIG. 2 is a back view thereof;

FIG. 3 is a left side view thereof;

FIG. 4 is a right side view thereof;

FIG. 5 is a top view of the ponytail hairnet; and,

FIG. 6 is a bottom view thereof.

The broken line outline of the partial human figure in FIGS. 1-4 assists in illustrating how the ponytail hairnet may appear when in a position of use, but forms no part of the claimed design.
